OF BERKELEY, CALIFORNIA

LIGHTING FIXTURE

Application filed June 8, 1928. Serial No. 283,849.

My invention relates to the types of indirect and semi-direct fixtures in which a lamp is surrounded by a screen which forms the body of the fixture, the body screen generally 5 acting also to reflect light upward to the ceiling or having a reflector placed therein for that purpose, and it relates particularly to the type in which light is also made to pass downward through an opening in the 10 fixture body screen for illumination below the fixture, part of the downward light being reflected upward again for illumination of the exterior of the fixture body, which otherwise would appear dark, and less attractive. 15 One object of my invention is to provide a lighting fixture having a body screen of pleasing form which can be more cheaply manufactured than those now in use, by cutting from sheet metal, and joining by soldering, brazing or spot welding instead of spinning to form, which is expensive, and prohibitive in cost for fixtures of large size.

Another object of my invention is to provide a lighting fixture having a body screen 25 which can be made in a variety of designs by cutting from sheet metal, and soldering, brazing, or welding to form, instead of by stamping, which requires expensive dies, and thereby limits the variety of designs that can 30 be profitably produced.

Still another object of my invention is to provide a lighting fixture having an indirectly illuminated body screen of pleasing form which can be made from sheet material 35 in plane surfaces or surfaces bent in only one direction so that the same may be conveniently and economically decorated in colors by means of stencils, cut from sheet material and applied or similarly bent, or by means 40 of flat castings or castings bent in only one direction.

Still another object of my invention is to provide a more convenient method of assembling a fixture having a body screen supported from arms, and of taking it apart for 45 cleaning, repairs, or other purposes.

Still another object of my invention is to provide means for obtaining a maximum amount of illumination without streaks or 50 shadows by projecting the direct rays of

light uniformly against the ceiling and side walls of a room as far down as a horizontal plane passing through the lamp, thus securing an effective illumination of the upper portion of the room and preventing the direct rays from coming lower down and being seen by a person standing in the room, and by illuminating the lower portion of the room by diffusion to a maximum degree so as to 55 secure a uniform blending of the portions of light at the line of intersection while preventing any glare in the eyes of a person standing up and facing the fixture. 60

The invention consists of certain novel features of construction, combination and arrangement of parts hereinafter described and particularly pointed out in the appended 65 claims.

In the accompanying drawing:

Figure 1 is a view in side elevation with 70 parts broken away to more clearly disclose the invention.

Figure 2 is a horizontal sectional view.

A lamp 10, of any suitable construction, but preferably of that type having its stem 75 provided with an enameled covering which extends downwardly to the horizon of the lamp filament, is fitted in a socket 11, having a cover or hood 12, from which extends a plurality of downwardly and outwardly flaring 80 hanger rods or arms 13, 13. Supported at the lower ends of these arms 13 is a suspending band or ring 14. The band 14 is provided on its inner surface with ears 15 for receiving the ends of two of the arms 13. The 85 ends of these arms are bent at right angles, as at 16, and are slidably inserted through the ears so as to have a slip-joint connection therewith for supporting the band or ring therefrom. The other or remaining arm 13 is provided with a loop or eye 17, into which a screw 18 is received, which passes through the ring or band 14. 90

With this construction the band 14 may be readily removed or applied to the lamp fixture by rotation relatively to the rods, as will be readily understood. The band or ring 14 is preferably located around the base of the bulb of the lamp 10, and projects a suitable distance below the lamp. Mounted upon 100

the band 14 and projecting upwardly therefrom is a body screen or reflecting shade 19, which may be of circular, polygonal or other suitable shape in horizontal section, but which, in accordance with my invention, flares upwardly and outwardly between its lower and upper edges along straight lines, that is to say, is not curved in vertical section. This screen or shade is provided with an inner reflecting surface while its outer surface is preferably made non-reflecting and of such character as to give a pleasing effect. The object of the straight line flare of the shield is to cause the direct light rays from the lamp to be projected symmetrically and with a uniformity of effulgence against the ceiling and side walls of a room without the streaks and shadows produced by screens of curved form in vertical section. The flare of the screen or shade may be uniform and continuous, but, in the present instance, I have shown a unitary double reflecting shade or screen comprising lower and upper halves or portions flaring acutely to different degrees, the upper portion or half to quite a pronounced degree greater than the lower portion or half, so that a wide spread of the light rays is obtained. Both portions of the shade or screen, however, flare along straight lines for the purpose stated. The point of juncture of these shade or screen portions is, as shown, in a horizontal plane close to and just below the horizon of the lamp filament, so that, with the fixture properly hung, the rays reflected more or less directly upward and to a certain degree outward by the lower frusto conical shade or screen portion of smaller size will be so disposed with relation to the rays projected upward and to a greater degree outward by the upper frusto conical shade or screen portion of larger size that a uniform distribution of the direct rays against the ceiling and down upon the side walls to a level corresponding to the horizontal plane of the lamp will be obtained. While this double frusto conical form of the shade or screen is preferred and is of great advantage in fixtures for use in medium and large sized rooms, I desire it understood that I do not limit the invention thereto, as a frusto conical shade or screen body of uniform flare may be used without loss of efficiency, particularly in fixtures for rooms of the smaller sizes. It is essential to my invention, however, whether the body consist of a single cone frustum or of two cone frustums, that its walls flare upwardly and outwardly on straight lines in order to secure the uniform distribution of the direct rays, without streaks or shadows, as hereinbefore set forth.

Supported from the shade or screen 19 and band 14 is a translucent light transmitting member 20. The member 20 is preferably made in the form of a shallow bowl having

the wall thereof projecting outwardly beyond the base or bottom of the screen 19 and its upper edge extending inwardly and upwardly within the confines of the ring or band 14, and the screen 19. Screws 21, 21 pass through the lower edges of the band or ring 14 and reflector 19 and engage the channeled neck or mouth of the reflector 20, for removably supporting it in position. This translucent member 20, by reason of its shallow form, will allow diffusion of a maximum amount of light from the lamp toward the floor for the purpose of illuminating the lower portion of the room without causing glare of the light into the eyes of a person standing in the room and looking toward the fixture. At the same time the shallow member 20 reflects the light upward into the body screen to reduce absorption losses and secure a higher degree of direct ray illumination in the upper part of the room. As the member is of greater diameter than the base of the reflecting shade or screen the light rays emanating from its peripherally projecting portion will strike the outer surface of the shade or screen and illuminate the same in a pleasing manner and prevent the exterior of the screen from appearing as a relatively darkened or shadowed surface. Such exterior illumination of the reflecting shade or screen will also be found most desirable when such surface is especially ornamented for display purposes.

In order to prevent the light issuing from the member 20 being directed horizontally when maximum wide-spread illumination of the lower portion of the room is not desired, an annular skirting shield or band 22 is arranged about the member 20 and supported from the ring or band 14 by arms 23 engaging the screws 21. This band may be of ornamental type to give a pleasing marginal appearance about the margin of the bowl 20 and, when the fixture is hung low, will shield from the light the eyes of a person standing up and looking directly toward the rim of the bowl.

From the foregoing it will be seen that the invention provides a novel form and arrangement of reflecting shade or screen for directing the direct light rays uniformly, and without streaks or shadows, against the ceiling and upper portions of the side walls of a room down to the horizontal plane of the lamp, and diffusing light downwardly through a bowl of novel type, so as to obtain maximum illumination without glare or other faults, while at the same time giving an attractive illumination of the fixture itself. By flaring the reflecting shade or screen on straight lines other advantages are gained, in that such shape of the screen adapts it to be made by cutting from sheet metal and soldering, brazing or welding to form, instead of by spinning to form which is expensive and prohibitive

in cost for fixtures of large size, or by stamping which requires expensive dies and thereby limits the variety of designs that can be profitably produced. Moreover, such shape of the shade or screen readily permits of its exterior ornamentation in colors by stencil-ing, allowing such ornamentation to be inex-pensively carried out.

Having thus described my invention, I claim:

1. In a lighting fixture, the combination, with a lamp having an upper stem portion and a lower bulb portion, the latter containing a filament, of a frusto-conical reflecting shade surrounding the bulb of the lamp for directing rays of light in an upward and outward direction, said shade extending above and below the horizon of the filament and having its walls inclined between its bottom and top upwardly and outwardly on straight lines, and a diffusing member at the base of the reflecting shade, said diffusing member being of greater diameter than the bottom of the shade and projecting marginally beneath the outer surface of the lower portion of the inclined wall of the shade so as to illuminate said surface.

2. In a lighting fixture, the combination, with a lamp having an upper stem portion and a lower bulb portion, the latter containing a filament, of a frusto-conical reflecting shade surrounding the bulb of the lamp for directing rays of light in an upward and outward direction, said shade extending above and below the horizon of the filament and having its walls inclined between its bottom and top upwardly and outwardly on straight lines, and a diffusing bowl having a neck portion secured within the base of the shade, said bowl being of greater diameter than the base of the shade and extending marginally beyond the same and beneath the outer surface of the lower portion of the inclined wall of the shade so as to illuminate said surface.

3. In a lighting fixture, the combination, with a lamp having an upper stem portion and a lower bulb portion, the latter containing a filament, of a frusto-conical reflecting shade surrounding the bulb of the lamp for direct-ing rays of light in an upward and outward direction, said shade extending above and below the horizon of the filament and having its walls inclined between its bottom and top upwardly and outwardly on straight lines, a light diffusing member arranged at the base of the shade and projecting marginally be-yond the same and beneath the outer surface of the lower portion of the inclined wall of the shade so as to illuminate the same, and an annular shield of greater diameter than the base of the shade and the diffusing member surrounding the latter so as to intercept hori-zontal rays therefrom and terminating at its upper edge in a plane adjacent to the upper surface of the projecting margin of the dif-

fusing member to form a passage for permitting light rays therefrom to shine upon said surface of the shade.

4. In a lighting fixture, the combination, with a lamp having an upper stem portion and a lower bulb portion, the latter containing a filament, of a frusto-conical reflecting shade surrounding the bulb of the lamp for direct-ing rays of light in an upward and outward direction, said shade extending above and below the horizon of the filament and having its walls inclined between its bottom and top upwardly and outwardly on straight lines, a light diffusing bowl having a neck portion secured within the base of the shade and a body portion projecting marginally beyond the sides of the base portion of the shade and beneath the outer surface of the lower portion of the inclined walls of the shade so as to illuminate the same, and an annular shield surrounding the body portion of the bowl for intercepting horizontal rays therefrom, said shield having its upper edge terminating immediately above the project-ing margin of the bowl to form a passage for the upward diffusion of light rays therefrom.

5. In a lighting fixture, the combination, with a lamp having an upper stem portion and a lower bulb portion, the latter containing a filament, of a frusto-conical reflecting shade surrounding the bulb of the lamp for direct-ing rays of light in an upward and outward direction, said shade extending above and below the horizon of the filament and having its walls inclined between its bottom and top upwardly and outwardly on straight lines, a supporting ring arranged within the base of the shade, supporting means for the shade engaging said ring, a light diffusing bowl having a neck portion secured within said ring and having a body portion projecting marginally beyond the sides of the base of the shade and beneath the outer surface of the lower portion of the inclined wall of the shade to illuminate the same, and an annular shield marginally surrounding the bowl and having its upper and lower edges terminating sub-stantially in the horizontal planes of the top and bottom surfaces of the bowl, the said upper edge of the shield being spaced from the base of the shade to permit of the upward passage of light from the margin of the bowl.

6. In a lighting fixture, the combination, with a lamp having a stem portion and a bulb portion, the latter containing a filament, of a unitary double reflecting shade surround-ing the bulb portion of the lamp and extend-ing above and below the horizon of the fila-ment and having a lower frusto-conical por-tion whose walls are inclined on straight lines at a certain upward and outward angle and an upper frusto-conical portion whose walls incline on straight lines at a greater upward and outward angle, and a light diffusing member arranged at the base of the lower

frusto-conical portion of the shade and projecting marginally beyond the same to cause light rays therefrom to illuminate the outer surface of said lower portion of the shade.

- 5 7. In a lighting fixture, the combination, with a lamp having a stem portion and a bulb portion, the latter containing a filament, of a unitary double reflecting shade surrounding the bulb portion of the lamp and extending above and below the horizon of the filament and having a lower frusto-conical portion whose walls are inclined on straight lines at a certain upward and outward angle and an upper frusto-conical portion whose walls incline on straight lines at a greater upward and outward angle, a light diffusing member at the base of the lower portion of the shade and projecting marginally beyond the outer surface of the inclined wall of said shade portion for illuminating the same, and an annular shield surrounding said member for intercepting and preventing passage of horizontal light rays therefrom and having its upper edge terminating adjacent to the horizontal plane of the upper surface of the diffusing member and spaced from the base of the shade to permit upward passage of light from said diffusing member.

8. In a lighting fixture, the combination, with a lamp having a stem portion and a bulb portion, the latter containing a filament, of a unitary double reflecting shade surrounding the bulb portion of the lamp and extending above and below the horizon of the filament and having a lower frusto-conical portion whose walls are inclined on straight lines at a certain upward and outward angle and an upper frusto-conical portion whose walls incline on straight lines at a greater upward and outward angle, and a light diffusing bowl having a neck portion secured within the base of the lower frusto-conical portion of the shade and having a body portion projecting marginally beyond the base of said lower portion of the shade for the upward passage of light rays to illuminate the outer surface of such portion of the shade.

9. In a lighting fixture, the combination with a lamp having a stem portion and a bulb portion, the latter containing a filament, of a unitary double reflecting shade surrounding the bulb portion of the lamp and extending above and below the horizon of the filament and having a lower frusto-conical portion whose walls are inclined on straight lines at a certain upward and outward angle and an upper frusto-conical portion whose walls incline on straight lines at a greater upward and outward angle, a light diffusing bowl having a neck portion secured within the base of said frusto-conical lower portion of the shade and having a body portion projecting marginally beyond the outer surfaces of the inclined walls of such portion of the shade to illuminate the same, and an annular shield arranged to surround the bowl to intercept and prevent the horizontal passage of light rays therefrom and having its upper edge terminating in proximity to the horizontal plane of the upper surface of the projecting margin of the bowl to form a space for the upward passage of light rays therefrom.

10. In a lighting fixture, the combination, with a lamp having a stem portion and a bulb portion, the latter containing a filament, of a unitary double reflecting shade surrounding the bulb portion of the lamp and extending above and below the horizon of the filament and having a lower frusto-conical portion whose walls are inclined on straight lines at a certain upward and outward angle and an upper frusto-conical portion whose walls incline on straight lines at a greater upward and outward angle, a supporting ring disposed within the base of the lower frusto-conical portion of the shade, fixture supporting means secured to said ring, a lamp diffusing bowl supported by the ring at the base of said lower portion of the shade and projecting marginally beyond the outer surface of the inclined wall of said portion of the shade to illuminate the same, and an annular shield surrounding the bowl to intercept and prevent the horizontal passage of light rays therefrom and terminating at its upper edge adjacent to the upper surface of the projecting margin of the bowl to form a space for the upward passage of light therefrom.

11. In a lighting fixture, the combination with a lamp supporting member, and a lamp supported thereby, of a plurality of arms extending from said supporting member, a hollow shade member surrounding said lamp and screening a portion of it from view, said shade member having a rotary slip-joint interlocking connection with certain of said arms and a detachable fastening connection with another of said arms, and a light transmitting and diffusing member supported at the base of said shade member.

12. In a lighting fixture, the combination with a lamp supporting member, and a lamp supported thereby, of a plurality of arms extending from said supporting member, a hollow shade member surrounding said lamp and screening a portion of it from view, said shade member and arms having interengaging elements to removably support the shade member on the arms, said interengaging elements being engageable and disengageable by relative rotary movement between said shade member and said arms.

In testimony whereof I affix my signature. 125
WHITMAN SYMMES.
